UNITED STATES PATENT OFFICE.

ZENSHIRO SUZUKI, OF LOS ANGELES, CALIFORNIA.

SHOE-FASTENING.

1,230,538.

Specification of Letters Patent. Patented June 19, 1917.

Application filed July 17, 1916. Serial No. 109,658.

To all whom it may concern:

Be it known that I, ZENSHIRO SUZUKI, a subject of the Emperor of Japan, residing at Los Angeles, in the county of Los Angeles and State of California, have invented a new and useful Shoe-Fastening, of which the following is a specification.

This invention relates to improvements in shoes and more particularly to fastenings therefor.

The primary object of the invention is to provide a shoe fastening for shoes of the button type in which the uppers overlap where fastened, which is exceptionally neat, concealed from view and not uncomfortable to the wearer.

The accompanying drawings illustrate the invention.

Figure 1 is a perspective view of the shoe provided with my improved fastening.

Fig. 2 is a fragmentary vertical sectional view taken through the shoe where fastened.

Fig. 3 is a fragmentary cross sectional view taken through the shoe where fastened.

Fig. 4 is an enlarged fragmentary detail sectional view of the fastening.

Fig. 5 is a top plan view of one of the fastening members.

Fig. 6 is a vertical sectional view of the fastening members shown in Fig. 7, and

Fig. 7 is a top plan view of the other of the fastening members.

Referring to the drawings, 1 designates as an entirety a shoe in which the upper 2 is open down the front and provides over-

lapping portions 3 and 4, the portion 4 overlapping the one 3. Secured along the edge of the portion 4 on the inner side thereof is a plurality of tongues 5 which are adapted to coöperate with keepers 6 therefor, the latter being secured to the portion 3 of the upper along the outer side and near the edge thereof.

Each of the tongues 5 is formed of a flat piece of metal which is rounded and reduced as at 7, at one end, and may have beaded edges 8 if so desired. Each tongue is provided with small openings 9 at the unreduced end thereof to provide for the sewing or fastening of the tongue to the shoe and is fastened so that it may be pulled away from the portion 4 sufficiently to permit its insertion into the keeper 6. Upon the inner face of each tongue intermediate the ends thereof is formed a rounded knob or protuberance 10. These tongues are secured in

close relation to one another, but sufficiently spaced apart to enable the manipulation thereof in fastening the shoe.

Each of the keepers 6 is provided with 60 offset ends that are fastened to the portion 3 as are the tongues 5, and is therefore spaced from the portion 3 of the shoe sufficiently to permit the tongues 5 to be inserted between them and the shoe.

The offset ends are formed by providing the flanges 11 at the ends of the keepers which are in the form of flat metal plates of rectangular outline, and projecting laterally from the flanges 11 are flanges 12 having a 70 series of apertures 13 therein. By means of these apertures 13 the keepers may be sewed or otherwise secured to the shoe. Each keeper is provided intermediate its ends and adjacent to one edge with a struck-out or bulged portion 14 which opens along one edge of the keeper. The knobs on the tongues 5 engage within the portion 14 and lock the tongues in coöperation with the keepers.

To fasten the shoe the portion 4 is brought into overlying relation to the portion 3 of the upper and the tongues 5 are inserted between the keepers 6 and opposed face of the portion 3, as shown in Figs. 3 and 4 of the drawings. The knobs or protuberances 10 upon the tongues 5 are forced between the portion 3 of the shoe and the keeper 6 and will snap into engagement with the portions 14 of the keeper so that the fastenings will 90 be locked.

To unfasten the shoe the tongues 5 are pulled out from coöperation with the keepers 6 into position shown in Fig. 4 of the drawings. The force required to unfasten the shoe is greater than that which will be exerted as a strain when the shoe is on the foot, and the fastenings will therefore serve to securely hold the shoe fastened upon the foot and will not cause the upper to bulge or prove unsightly and uncomfortable.

One of the most essential features of this invention is that the fastening elements lie flat and in close relation to the shoe. Another advantage over the old and well known fastenings for shoes is that with my improved fastening the shoes may be secured with much more ease and rapidity.

I claim:

1. A fastening comprising a flat tongue provided intermediate its ends with a protuberance and adapted to be secured at one

end to the uppers of a shoe, a keeper for co-operation with the tongue and having its ends offset and adapted to be secured to a shoe, said tongue adapted to extend under the keeper, said keeper having a struck-out portion formed intermediate its end and communicating with the longitudinal edge thereof farthest removed from the tongue, said struck-out portion being spaced from 10 the side of the keeper opposed to the tongue, said protuberance adapted to engage in said struck-out portion.

2. A fastening comprising a flat tongue having a protuberance formed intermediate 15 the ends thereof and provided at one end with openings to receive fastening means,

said tongue adapted to be secured to a shoe and having its free end rounded and reduced, a keeper adapted to be secured to the shoe and having a struck-out portion intermediate the ends thereof and adapted to receive the protuberance on the tongue, said struck-out portion being spaced from the edge of the keeper that is opposed to the tongue and opening out upon the other longitudinal edge of the keeper. 20 25

Signed at Los Angeles, California, this 1st day of July 1916.

ZENSHIRO SUZUKI.
